ELECTRIC LANTERN

Nolan K. Rhoades, Beloit, and Ralph T. Jacobsen, Stoughton, Wis., assignors to The Electric Storage Battery Company, Philadelphia, Pa., a corporation of New Jersey

Filed May 25, 1964, Ser. No. 80,133

Term of patent 14 years

(Cl. D48—24)

FIG. 1

FIG. 2

FIG.3

FIG.4

FIG.5

FIGURE 1 is a side elevation of an electric lantern, showing our new design;

FIGURE 2 is a top plan view thereof;

FIGURE 3 is a front elevation thereof;

FIGURE 4 is a rear elevational view thereof; and

FIG. 5 is a fragmentary front elevation of a modified form of the lantern disclosed in FIG. 1, the difference residing in a single switch button.

The stippling shown in FIG. 1 is to be understood as continuous throughout the corresponding vertical sides shown in FIGS. 3 and 4 and indicates contrast. The undisclosed side of the lantern is substantially the same as the side shown in FIG. 1.

We claim:

The ornamental design for an electric lantern, as shown and described.
